UNITED STATES PATENT OFFICE.

CHARLEY F. WENDEL, OF LAKEFIELD, MINNESOTA.

ADJUSTABLE SUPPORTING-FRAME.

1,235,405.

Specification of Letters Patent. Patented July 31, 1917.

Application filed December 5, 1916. Serial No. 135,174.

To all whom it may concern:

Be it known that I, CHARLEY F. WENDEL, a citizen of the United States, and resident of Lakefield, in the county of Jackson and 5 State of Minnesota, have invented certain new and useful Improvements in Adjustable Supporting-Frames, of which the following is a specification.

The present invention relates to supports 10 and has particular reference to a new and improved construction of supporting frame for milk strainers and the like when used in connection with the reservoirs of milk and cream separators.

15 My invention contemplates the provision of an adjustable frame for supporting strainers or the like above other larger receptacles, the device embodying two slidably connected sections adapted to span the 20 width of the reservoir, said sections being formed preferably of strands of wire bent in a novel manner to provide a strong and durable, useful article, which may be cheaply manufactured and placed on the 25 market at small cost.

30 My invention further contemplates the provision of an article of the class referred to which may be used in connection with round or square reservoirs and may be utilized to support one or more objects.

35 Other objects of my improved support not hereinbefore set forth will appear from the following detailed description and the claims, taken with an inspection of the accompanying drawing, in which:

Figure 1 is a perspective view of a milk and cream separator reservoir showing my improved supporting frame in use;

40 Fig. 2 is a similar view showing the device in use in connection with the reservoir of a different shape; and

Fig. 3 is an enlarged perspective view of the supporting device of my invention.

45 Referring more particularly to the drawing, wherein similar characters of reference designate like and corresponding parts throughout the various views, and with specific reference to Fig. 3 I provide a supporting frame embodying a pair of adjustably and slidably connected sections designated 50 S and S' in their entireties. One of the sections, namely, the section S, is provided with an arm a extending at right-angles thereto and adapted to coöperate with the 55 sections, in a manner which will hereinafter appear.

The sections S and S' as well as the arm a are all formed of strands of wire.

Referring specifically to the section S the same is composed of a single strand of wire 60 forming the arm a, one free end of said strand having a looped end formed thereon, said loop terminating in a laterally extending finger 11. The strand of wire forming the arm a and section S is looped intermediate its ends to provide an eye 12, said strands being bent at right-angles to the arm a to form the section S. The right-angularly bent portion of the strand is designated 13, said portion being bent upon 65 itself to form an arm 14 arranged in spaced parallel relation thereto. The arm 14 extends through and beyond the eye 12, the free end of said arm 14 having an eye 15 formed thereon in concentric relation to 70 the eye 12.

The section S' is composed of a strand of wire bent upon itself to form parallel arms 16 and 17 embraced by the loop 15 and slidably therein, both of said arms 16 and 17 80 extending through the eye 12 and slidably therein. The arm 16 is extended beyond the arm 17 and formed with an eye 18 to embrace the arms 13 and 14. The arm 17 is bent laterally as at 19 to form a stop for 85 engagement with the portion 20 of the arm a. The free ends of the sections S and S' are laterally bent to form fingers 21 and 22 for coöperation with the finger 11 hereinbefore referred to. 90

In use the device is applied either in the position shown in Fig. 1 or in that shown in Fig. 2. In Fig. 1 a circular receiving reservoir for milk and cream separators has been shown and designated R. A strainer is 95 shown and designated s. To support the strainers over the reservoir the sections S and S' of my improved frames are disposed diametrically of the reservoir, the fingers 11, 21, 22 engaging the peripheral margin of 100 said reservoir. In the space between the arm a, one of the sections, and the peripheral wall of the reservoir the strainer s is disposed as best shown in Fig. 1.

In Fig. 2 a rectangular form of reservoir 105 has been shown and designated R'. The strainer is shown and is mounted in this instance much in the same manner as when applied to the circular reservoir. Of course, I do not limit myself to the use of my improved strainer support as such, since the same may be adapted to numerous uses with 110

advantages. I desire to direct especial attention to the novel and light construction of the supporting device as well as its adjustable features and cheapness of construction.

From the above description taken in connection with the accompanying drawing, it is thought that a clear and comprehensive understanding of the construction, operation and advantages of my invention may be had, and while I have shown and described the device as embodying a specific structure, I desire that it be understood that such changes may be made in said structure as do not depart from the spirit and scope of the invention as claimed.

Having thus fully described my invention, what I claim as new and desire to secure by Letters Patent, is:—

1. In a support frame, a pair of adjustable sections formed of strands of wire, one of said strands being looped intermediate its ends to provide an eye and right-angular portions, one of said right-angular portions being bent upon itself to form parallel spaced arms, the free arm extending through and beyond said eye and having an eye upon the free end thereof, a second strand being bent intermediate its ends to form parallel arms slidable through both of said eyes, one of the arms having an eye to embrace the first said spaced arms and the other arm being bent to form a stop, and means formed on the free ends of said arms adapted to engage the wall of a receptacle to retain the supporting frame in the desired position.

2. In a support frame, a pair of adjustable sections formed of strands of wire, one

of said strands being looped intermediate its ends to provide an eye and bent at right-angles to form arms, one of said right-angular arms being bent upon itself to form parallel spaced portions, the free portion extending through and beyond said eye, the free end of said elongated portion having a loop thereon, the right-angular portions first mentioned being in spaced relation, a second strand of wire bent intermediate its ends to form parallel arms slidably mounted in said eyes, one of said arms being extended and looped to embrace said parallel spaced portions, and the other arm being bent laterally for movement between said spaced parallel portions to form a stop adapted to engage the first mentioned eye to limit the movement of said sections.

3. In a support frame, a pair of adjustable sections formed of strands of wire, one of said strands being looped intermediate its ends to provide an eye and bent to form right-angular portions, one of said portions being bent upon itself to form parallel arms, one of said arms being elongated and extending through said eye, the second strand being bent upon itself to form parallel arms embraced by said eyes, one of said arms being looped about first said parallel arms, and the other of second said arms being bent laterally to form a stop member movable between said parallel spaced arms and adapted to engage the portion of first said strand at right-angles to said arm to limit the outward or extended movement of said sections.

In testimony whereof, I affix my signature hereto.

CHARLEY F. WENDEL.
